UNITED STATES PATENT OFFICE.

FRANK R. HAHN, OF DECATUR, ILLINOIS.

BUILDING CONSTRUCTION.

1,165,668.

Specification of Letters Patent. Patented Dec. 28, 1915.

Application filed March 30, 1914. Serial No. 828,153.

To all whom it may concern:

Be it known that I, FRANK R. HAHN, a citizen of the United States, residing at Decatur, in the county of Macon and State 5 of Illinois, have invented certain new and useful Improvements in Building Construction, of which the following is a specification.

My invention relates to improvements in 10 building construction and particularly to that type of construction utilizing cement or plastic units.

The principal object of this invention is 15 the provision of a two part block having tongued and grooved edges with a water proof material interposed therebetween and extending into said grooves.

To the accomplishment of the foregoing and such other objects as may hereinafter 20 appear, my invention consists in the combination, construction and arrangement of parts hereinafter described, and then sought to be defined in the appended claim, reference being had to the accompanying drawings 25 forming a part hereof, and which shows merely for the purpose of illustrative disclosure, a preferred embodiment of my invention, it being understood that various changes may be made in practice within the 30 scope of the claim, without digressing from my inventive idea.

Figure 1 is a perspective view of one form of tile. Fig. 2 is a perspective view of the 35 two parts forming a tile constructed according to my invention. Fig. 3 is a perspective view of a completed tile.

Attention is first directed to Fig. 1, wherein is shown one form of tile, constructed according to my invention. This tile has 40 two edges grooved as indicated at 2 and two edges provided with the V-shaped projections 3 corresponding to said grooves, whereby adjacent tiles are fitted together. On each side of these grooves 2 and edges 45 3 are the bearing shoulders or flanges 4, which provide means whereby the blocks or tiles may be supported one upon the other, without the possibility of the wall or partition being broken to pieces or falling, these 50 horizontal flanges providing a secure base for the tile or block next above.

It is also to be noted that each tile or

block is provided with the metallic reinforcing 5 in the form of a netting, having the suitable end members 6 which are embedded in the relatively enlarged end portion 7 of the tile or block. The tile or block as is shown, is paneled on either side for the purpose of adding to its artistic value and attractiveness, the reinforcement strengthening 60 the tile so that this panel effect does not detract from its normal strength, durability and utility.

Each tile comprises the two parts 8 of the same size and shape which coöperate to 65 provide a block having the V-shaped grooves and edge extensions 9 and 10 similar to those shown in Fig. 1. The two parts of this block are paneled as shown at 11, said panels being provided on the inner side of 70 the two parts. These two parts are adapted to be placed together substantially as indicated in Figs. 2 and 3 and have a suitable water-proof paper or material 12 interposed therebetween, so as to prevent the two parts 75 contacting, this interposition of a water-proof material preventing the passage of dampness therethrough, and being a material advantage. It is to be noted that this water-proof material or paper 12 is extended to fit the V-shaped grooves 9 so that when the adjacent tile or block fits therein, the two blocks will not contact directly with each other and the joint will be water-proof.

What I claim is:

A block or tile formed of two parts corresponding in shape and size to provide a plurality of the edges with V-shaped grooves and a plurality of the edges with V-shaped tongues or extensions, whereby adjacent 90 tiles may be interlocked, and a water-proof material interposed between said two parts and extending into said grooves so as to provide grooves with their sides of water-proof material, so that the adjacent blocks 95 or tiles do not contact directly with each other.

In testimony whereof I affix my signature in the presence of two subscribing witnesses.

FRANK R. HAHN.
